MAXMOOR CORPORATION, OF NEW YORK, N. Y., A CORPORATION OF DELAWARE.

INTERIOR AGITATOR FOR INTERNAL-COMBUSTION ENGINES WITH REMOVABLE CYLINDER HEADS.

Application filed January 8, 1927. Serial No. 159,838.

My invention is of an interior agitator for internal combustion engines consuming volatile liquid fuel and provided with removable cylinder heads.

5 Agitating devices in accordance with my invention are formed from a sheet, plate or the like and are readily, simply and securely held in place by interposition of such sheet, plate or the like between the engine cylinders 10 and the removable cylinder head.

One of the interposed members may be supplied for each engine cylinder or for a plurality of cylinders less than the whole number of cylinders in the cylinder block, 15 but preferably a single member having the general form and outline of the junction surfaces of cylinder block and removable cylinder head is supplied and equipped with agitating blades or vanes for each cylinder.

20 Such members are preferably of metal and may conveniently be stamped out of sheet metal. Heat and corrosion resisting metal is preferably used, as, for example, silicon-chromium-steel is well adapted for this purpose. When desired, the vanes may be coated with a catalyst, or the sheet metal may comprise elements which upon exposure to 25 the hot gases with resulting surface oxidation, are adapted to exert a catalytic effect

30 during combustion of the charge after it has been ignited, as by means of the usual spark plug. For example, oxides of aluminum appear to have a beneficial catalytic action during combustion and may be developed by the 35 surface oxidation of alloys containing this element. Alloy steel containing about 2% each of aluminum and silicon and about 8% of chromium with relatively low carbon is well adapted for my purpose, having high

40 red hardness and resistance to scaling when subjected to hot oxidizing gases, while such surface oxides as are formed comprise the catalytically active oxide of aluminum. Use of special alloys, while desirable, is not essential and materials such as ordinary black 45 iron may be used.

These interposed members may take the place of the usual gasket by being surfaced with compressible gasketing material, such as 50 asbestos sheets, in which case they may be substituted at manufacture for the usual gasket, and their installation on old engines as an accessory involves no more than the replacement therewith of the original gasket

supplied with the engine. If the members 55 are not so surfaced, two separate gaskets are preferably provided with the agitator member between them. In either case the interposed member is provided with holes like the gasket, whereby effective cooling of such 60 member is obtained by extensive exposure to the cooling jacket water.

In the accompanying drawings, Fig. 1 is a vertical sectional view of an L-head four-cycle internal combustion engine equipped with agitator means in accordance with my invention. Fig. 2 is a plan view showing the agitator member in place on the cylinder block ready for the attachment of the removable cylinder head, and Fig. 3 is a plan view 70 of a sheet metal blank prior to the twisting of the vanes to their final form by the finishing die.

Reference character 10 indicates the cylinder block and 12 the removable cylinder head 75 of an internal combustion engine. The internal combustion engine shown is of the L-head four-cycle type having intake valves 14 and exhaust valves 16. The spark plug 18 is preferably located over the intake valve 80 14.

Reference character 20 designates a flat member made from a metallic sheet or plate and interposed between the cylinder block and the cylinder head, and 22, 24 designate 85 gasketing material which may either be secured directly to the top and bottom of member 20, thus making up a combined gasket and agitator plate member, or separate top and bottom gaskets may be provided, and 90 made use of and handled independently of the plate member.

The member 20 and the gaskets or gasketing surfaces 22, 24 are provided with the usual bolt holes 26 for receiving bolts 28 to 95 secure the cylinder head in place, and with the usual water jacket communication holes 30.

In blanking out the plate member 20, instead of making the usual holes that are 100 formed in the ordinary gasket for each cylinder, a modified opening is made leaving a plurality of, preferably three, tongues 32, 34 and 36 of the sheet material projecting substantially radially into the opening 38 provided at each cylinder bore 40. Where three such tongues are formed, they are preferably arranged, in the case of an L-head engine,

substantially as shown, one at that end of the combustion chamber 42 which is opposite the end thereof containing the valves, and one on each side thereof at an angular distance 5 around the opening 38 of substantially 120° of arc.

After blanking, or alternatively, in the same operation, the tongues 32, 34 and 36 are bent or twisted angularly so as to form inclined vanes 44, 46 and 48, which may make any desired angle with the cylinder axis. As shown, the vanes make an angle of about 45° with the cylinder axis, but the angular formation may obviously be varied as desired. 10 The vanes in addition to preferably having catalytic surfaces or coatings thereon, whereby the catalyst is located in the most favorable position for securing effective catalytic action in the promotion of combustion after 15 ignition of the charge, have two principal functions as follows:

They produce violent agitation and thorough admixture of the charge components, which agitation is largely of a cyclonic nature, the 20 gases in the cylinder and combustion chamber being substantially sliced onto parts by the vanes and caused to rotate in one direction on the downward movement of the piston during the intake stroke, and in the opposite direction on the compression stroke. Thus at 25 ignition toward the end of the compression stroke all the confined gases, including the newly admitted charge mixture and the residual or unscavenged gases, are homogeneously 30 admixed and all parts thereof are in a state of violent agitation and the rapidly moving gases quickly spread the flame throughout the combustion chamber. The violence of agitational movement of the confined gases varies 35 with the engine and piston speed, being least violent at low speeds and more violent at high engine speeds. As this variation in agitational movement and, therefore, in speed of flame propagation is substantially equivalent in effect to retarding the spark at low 40 speeds and advancing it at high speeds, there is much less need for control of spark timing than with ordinary engines, and the engine 45 can be run quite satisfactorily with fixed ignition.

The vanes absorb heat during combustion and retain much of this heat of the prior cycle through the exhaust stroke and give it up in large part to the incoming gases of the next 50 cycle. Where the incoming gases contain fuel in ungasified state this heat is largely expended in producing completed gasification of the fuel and such temperature rise as is caused is not materially productive of loss of 55 volumetric efficiency. Further, the charge is practically all in the cylinder and confined therein by the time that the transfer of heat from the vanes to the charge is effected, and much more heat can be supplied to the charge 60 gases by the vanes within the heart of the con-

fined charge without causing loss of volumetric efficiency than would be possible if the heat were supplied to the charge before entering the cylinder and while it has yet to traverse the relatively narrow intake passages 70 and to get past the intake valve. The vanes being cooled by the jacket water and by the transfer of heat to the charge are in a state for absorbing any excess heat during combustion and in this way serve to prevent any 75 part of the rapidly moving charge gases from reaching a temperature productive of detonation. The cyclonic agitation of the charge also serves to substantially scrub or scour any adhering insulating gas film from 80 the jacket walls and promotes efficient transfer of heat to the jacket walls. Should pressure waves be set up following ignition they are broken up when coming into contact with 85 the vanes.

With the thorough admixture and resulting homogeneity of the cylinder contents obtained by the use of the agitator vanes much leaner mixtures can be used with resulting fuel economy, and the residual products of combustion remaining in the cylinder to be admixed with the incoming charge can be increased to considerable advantage in the way of working at higher compression ratios without consequent detonation. For example, the exhaust valves may be timed for late closing so that a proportion of the exhaust gases are drawn back into the cylinder during the early part of the intake stroke, or in some cases the exhaust valves may close early to trap a 100 measured volume of exhaust gas and in such case a late opening for the intake valves is desirable. Change in valve timing is, however, not at all essential, as the vanes produce marked improvement in engines without resorting to changes in valve timing. Provision is preferably made to supply hot air through the carburetor for low throttle openings and cold air at wider throttle openings 105 up to full open throttle.

The scope of my invention is defined in my claims, the embodiment illustrated being for affording an understanding of the invention and not for the limitation thereof.

The subject matter of my invention disclosed in this application and not claimed therein is disclosed and claimed in my copending application Serial No. 155,919, filed December 20, 1926.

I claim:

1. An internal combustion engine comprising a cylinder, a cylinder head therefor, and a member secured between said cylinder and said cylinder head and having an opening therethrough aligned with the bore of said cylinder, and a vane integral with said member projecting from the edge of said opening and extending substantially from the edge of the cylinder bore towards the center thereof; said vane being inclined transversely 125

relative to the longitudinal axis thereof for imparting a cyclonic movement to the fuel charge.

2. An internal combustion engine comprising a cylinder, a cylinder head therefor, and a gasket secured between said cylinder and said cylinder head and having a vane integral therewith projecting therefrom, and extending substantially from the edge of the cylinder bore towards the center thereof; said vane being inclined transversely relative to the longitudinal axis thereof for imparting a cyclonic movement to the fuel charge.

3. An internal combustion engine comprising a cylinder, a cylinder head therefor, a plate secured between the same, and having an opening alined with the bore of said cylinder, and inclined vanes projecting from the edge of said plate about said opening towards the center thereof.

4. An internal agitator for an L-head four-cycle internal combustion engine for consuming volatile liquid fuel, comprising a plate interposed between the cylinder and cylinder head and provided with three integral inclined vanes projecting inwardly over the space swept by the piston, one of said vanes being arranged substantially on the major axis of the combustion chamber, and substantially opposite the valves, and the other two at intervals of substantially 120° of arc around the cylinder bore.

5. A plate of metal interposed between the cylinder and cylinder head of an internal combustion engine and having an opening aligned with the cylinder bore and a vane integral with said plate projecting transversely of said opening and over the cylinder bore, and inclined transversely relative to the longitudinal axis of the vane, whereby to impart a cyclonic movement to the charge mixture as the same sweeps over said vane upon reciprocating movement of the piston.

6. An internal agitator for internal combustion engines, comprising vanes with catalytic surfaces supported in the combustion chamber over the space swept by the piston.

7. An internal agitator for internal combustion engines, comprising vanes of metallic alloy containing aluminum supported in the combustion chamber over the space swept by the piston and adapted upon surface oxidation to exert a beneficial catalytic effect during combustion.

8. An internal agitator for internal combustion engines composed of alloy steel containing approximately 2% each of silicon and aluminum, 8% of chromium, and the principal part of the remainder iron.

9. An internal combustion engine comprising an engine cylinder having a combustion chamber at the end thereof, a piston in said cylinder, and a member above said piston having an opening therein alined with the bore of said cylinder, and an edge portion

about said opening lying in proximity to a point in alinement with the edge of said piston, and a transversely inclined member projecting from the edge portion of said member about said opening and extending over the end of said piston from substantially the edge thereof towards the center thereof; said transversely inclined member serving to impart a cyclonic agitational movement to the fuel charge, and having substances incorporated therein for exerting a catalytic action on said charge during the agitation thereof.

10. An internal agitator for internal combustion engines comprising a transversely inclined vane projecting inwardly into the combustion chamber over the space swept by the piston for imparting a cyclonic agitational movement to the fuel charge, said vane consisting of a metal resistant to corrosion when hot, and incorporating substances for exerting a catalytic action on the fuel charge during the agitation thereof.

11. An internal combustion engine comprising a cylinder, a cylinder head therefor, a plate secured between the same and having an opening registering with the bore of said cylinder of a cross-sectional area substantially as large as that of said bore, and a vane projecting from the edge of said opening and extending substantially from the edge of said bore inwardly; said vane being inclined transversely relative to the longitudinal axis thereof for imparting cyclonic movement to the fuel charge.

12. As a new article of manufacture, a metallic member corresponding in outline to the junction surfaces of an internal combustion engine cylinder block and its cylinder head, and provided with bolt holes and water jacket communication holes, and with a cylinder opening, and having an inclined vane projecting from the edge of said member about said cylinder opening, and extending inwardly.

13. An internal combustion engine comprising a cylinder, a cylinder head therefor, and a separate member secured between and retained in position by said cylinder and said cylinder head, and having an opening alined with the cylinder bore, and inclined vanes projecting from the edge of said member about said opening towards the center thereof.

14. As a new article of manufacture, a metallic plate corresponding in outline to the junction surfaces of an internal combustion engine cylinder block and its cylinder head, and provided with bolt holes and water jacket communication holes, and with cylinder openings, and having inclined vanes integral with the material of the plate extending substantially radially inwardly about the cylinder openings.

In testimony whereof, I have signed my name hereto.

ARLINGTON MOORE.
